SAMUEL SHAFFER, JR., AND LLOYD H. DRAEGER, OF MILWAUKEE, WISCONSIN, AS
SIGNORS TO CHAIN BELT COMPANY, OF MILWAUKEE, WISCONSIN, A CORPORATION
OF WISCONSIN.

HOIST MECHANISM FOR POWER LOADERS.

Application filed February 27, 1924. Serial No. 695,461.

This invention relates to loading apparatus in which a vessel that receives the load or charge is periodically moved from a receiving to a discharging position; and the invention has for its object to apply the power that moves said charging vessel to advantage, to simplify the construction of the mechanism by which the loading vessel is operated, and to arrange these so that the vertical dimensions of the apparatus when in positions of rest are reduced to the minimum. Our invention is primarily intended for use in connection with a charging or loading skip for a concrete mixer, whose movements are controlled by a cable; we wish it to be understood, however, that the invention in its useful applications is not limited to a loader for concrete mixers, but rather is adapted for a wide variety of uses.

In the accompanying drawings—

Figure 1 is a side view of a loading skip or hopper for a concrete mixing machine, to which our invention is applied, the receiving position of the skip and its associated and cooperating parts, being represented in full lines, the discharging position thereof by dotted lines, and an intermediate position by dot and dash lines.

Fig. 2 is a rear elevation of the apparatus.

In the accompanying drawings, A designates the framework of a concrete mixing machine, the drum of which is designated B. C represents the loading skip or hopper into which, when resting upon the ground or in a lowered position, a charge of materials to be mixed is delivered, and which when moved to the position indicated by dotted lines in Fig. 1, discharges such charge into the drum B. The skip C is formed with a forward spout section c and a rear loading section adapted to rest upon the ground when the skip is lowered, the latter section preferably having flaring side walls to give capacity to the loader without unduly increasing its length, as represented in Fig. 2. The spout portion c of the skip has secured to its opposite sides the bars D which are pivotally connected, at E, E, with the frame of the machine. The parts thus far described are well known in the art and serve to locate the pivot of the skip in advance of the nose or forward end of the spout section c thereof.

2, 2 indicate a pair of stifflegs pivotally secured, at 3, 3, to the frame of the machine, at the opposite sides thereof, being located such distance apart as to permit the spout section c of the loading skip to lie and move between them. The pivots 3 are to the rear of the pivots E, connecting the skip to the frame A, and preferably at a lower level. The upper, outer, portions of the stifflegs are pivotally connected with the skip by links 11, 11, preferably formed of rigid material, the pivotal connection with the stiffleg being indicated at 4, and that with the hopper portion of the skip at 12. It will be noted that the connections between the stifflegs and the skip, formed by the links 11 are of fixed length, that is to say, they are not lengthened or shortened during the operation of the apparatus.

The cable 5 by which the movements of the skip are controlled has its outer end connected to the upper, outer, end of the stiffleg 2, as indicated at 4. In the arrangement shown the cable passes to and across an idler sheave or pulley 6 supported in the upper part of the frame A, and thence downward to a winding drum 7, mounted in the lower portion of the framework. On the shaft that carries the winding drum is supported a large drum or bull wheel 8 to which is secured a cable 9 leading to the power driven winding drum 10. The parts which have been referred to, such as the stifflegs, links 11, and cable 5, may be duplicated, as is the preferred arrangement when the skip is of large capacity and subject to uneven loading; or there may be but one of each of the said parts, in which event the connection with the skip and the arrangement of the parts would be in the plane of the longitudinal center of the skip or loading vessel. We therefore in describing the operation of the apparatus and in the following claims, refer to these parts in the singular number, with the understanding that they may be duplicated or not, as circumstances may require. The pulleys 6 are located at the sides of the framework of the machine so that the cables 5 are but little diverted, laterally, in passing from the ends of the stifflegs to such pulleys.

The parts of the apparatus illustrated being in the position represented by full lines in Fig. 1, a position occupied by the skip or vessel C while receiving its charge, if

power be applied to the cable 9, by rotating the drum 10, the cable 5 will be wound upon the drum 7, swinging the stiffleg 2 upwardly and forwardly. This movement will be communicated to the skip through the connecting links 11. Owing, however, to the location of the pivots E and 3, of the skip and stiffleg, respectively, and to the arrangement of the link 11, the stiffleg and skip have differential movements. The arc traversed by the skip, from its loading to its discharging positions, being greater than that traversed by the stiffleg.

In the drawings an intermediate position of the parts, between those just referred to, is indicated by dot and dash lines.

It will be seen that by the arrangement described the parts of the mechanism employed for controlling the movements of the skip do not extend much, if any, above the framework A of the machine. This is a fact of practical importance, since it permits the machine to be moved in transit, and to be manipulated, in positions that could not be occupied by the machine were the operating parts located high above the drum and other moving parts of the mechanism, as has heretofore been the practice.

What we claim is:—

1. The combination with a supporting frame and a loading skip pivotally united

thereto, of a stiffleg pivoted to the frame at a point to the rear of and below the pivot for the loading vessel, the stiffleg extending from its pivot upwardly and rearwardly so that its upper end is above the hopper portion of the loading skip, a rigid link pivotally connecting the upper, outer, end of the stiffleg with the hopper portion of the skip, a cable by which the movements of the skip are controlled, secured to the stiffleg and a winding mechanism for the cable mounted in the supporting frame.

2. In a loader for a concrete mixer, the combination with a supporting framework, a mixing drum mounted therein, and a pivoted loading skip arranged to deliver to the drum when elevated, having a delivery spout section and a loading section that flares towards its outer or rear end, of a pair of stifflegs pivoted to the framework and extending rearward, one on each side of the skip, a pair of rigid links, one between the upper end of each stiffleg and a side of the flaring portion of the skip, a pair of pulleys located one at each side of the framework, cables extending from the free ends of the stifflegs over the pulleys, and means for winding up the cables.

SAMUEL SHAFFER, JR.
LLOYD DRAEGER.
